WINDSHIELD

Filed Sept. 9, 1921

Inventor:
Albert B. Mueller
By G. L. Cragg Atty.

UNITED STATES PATENT OFFICE.

ALBERT B. MUELLER, OF CHICAGO, ILLINOIS, ASSIGNOR TO AUGUSTUS EHLE, OF CHICAGO, ILLINOIS.

WINDSHIELD.

Application filed September 9, 1921. Serial No. 499,524.

To all whom it may concern:

Be it known that I, ALBERT B. MUELLER, citizen of the United States, residing at Chicago, in the county of Cook and State of Illinois, have invented a certain new and useful Improvement in Windshields, of which the following is a full, clear, concise, and exact description.

My invention relates to wind shields employed in automobiles and particularly to those wind shields that are made up of main and supplemental shields, the latter being commonly termed wind shield wings.

My invention has for its object the provision of an improved assembling structure for coupling the supplemental wind shields with the frames of main wind shields.

In carrying out my invention a carrier is provided for each supplemental wind shield, this carrier being coupled with one side of the corresponding main wind shield frame. Clamps are provided upon the carrier that grip opposite sides of the supplemental shield, each clamp comprising a back portion upon one side of the supplemental shield, a member upon the other side of the supplemental shield and in hinged connection with said back portion, and means for forcing the hinged member toward the supplemental shield.

In the preferred embodiment of the invention ears are connected with the back portion of each clamp, the back portion being upon one side of the supplemental shield and the ears being upon the other side of the supplemental shield. A member is in hinged connection with said ears, there being a screw in threaded connection with the outer portion of the hinged member and, when turned, engaging said back portion to force the inner portion of the hinged member toward the supplemental shield.

The back portion of each clamp preferably has a threaded stem upon it that passes through the supplemental shield carrier. A nut is upon each threaded stem, the carrier for the supplemental shield having portions interposed between said nuts and the clamp body portions.

I will explain my invention more fully by reference to the accompanying drawing showing the preferred embodiment thereof and in which Fig. 1 is a view in elevation illustrating a portion of a main wind shield

and a supplemental shield assembled therewith; Fig. 2 is a perspective view showing one of the supplemental wind shield clamps; Fig. 3 is a view, in elevation, of one of the supplemental shield clamps, the threaded 60 stem portion thereof being shown in section as are also the adjacent parts of the supplemental shield carrier and the clamping nut upon the threaded stem; Fig. 4 is a perspective view showing the back portion of one 65 of the clamps with the ears and threaded stem thereon, the hinged member being removed; Fig. 5 is a perspective view of the hinged member; and Fig. 6 is a view looking toward the stem side of the clamp. 70

Like parts are indicated by similar characters of reference throughout the different figures.

I have shown a portion 1 of a transparent main wind shield which may be of any well 75 known or suitable construction. Said shield is provided with any suitable form of frame of which a portion 2 is illustrated. The main wind shield may be provided with two transparent side wings or supplemental 80 transparent wind shields 3. Each supplemental wind shield is supported by a carrier 4 that is coupled with the adjacent side of the main wind shield frame by any suitable means such as the clamping devices 5. The 85 carrier 4 is preferably of U-form, though it is not to be limited to such shape. As illustrated, the ends thereof are provided with caps 6 that are assembled in any suitable way with the carrier as by means of pins 7. 90 Each end of the carrier 4 is assembled with the supplemental shield 3 through the intermediation of the clamps of my invention. Each of such clamps comprises a back portion 8 upon one side of the corresponding 95 supplemental shield 3, ears 9 connected with said back portion and upon the other side of the corresponding supplemental shield 3, a member 10 interposed between the ears 9 and placed in hinged connection therewith 100 by means of a pintle 11 passing through openings 12 in the ears 9 and the openings 13 in the hinged member 10, and a spreading device or devices, preferably in the form of screws 14, in threaded connection with 105 the outer portion of the corresponding hinged member 10 and, when suitably turned, engaging the back portion to force the inner portion of such hinged member toward the supplemental shield which is 110

thereby clamped between this inner portion of the hinged member and the back portion 8 upon which this member is hinged. The clamps are preferably made of metal and are therefore desirably lined with a rubber or other suitable packing 15 that directly embraces the adjacent portion of the supplemental shield and prevents the shield from being broken as a consequence of the clamping pressure exerted thereon by the screws 14. Each clamp thus constructed desirably carries a threaded stem 16 upon the portion 17 that connects the ears 9 with the back portion 8, the portion 17 being in the plane of the supplemental shield. The stem 16 thus carried upon the back portion of each clamp extends through an opening formed in the outer and flat portion of the corresponding cap 6. A winged nut 18 is threaded upon each stem 16 and clamps the flat end of the corresponding cap 6 against the shoulder 19 that is at the base of the corresponding stem 16 and which projects outwardly beyond and is carried by the clamp portion 17.

In the type of supplemental wind shield shown the bottom edge thereof is substantially horizontal and the top edge slopes inwardly and on this account the threaded stem 16 of the upper clamp is at an obtuse angle to the balance of this clamp so as to be in alignment with the threaded stem of the bottom clamp, this latter stem being at right angles to the clamp carrying it.

The bodily position of the supplemental shield may be determined by swinging its carrier upon the frame of the main shield. The supplemental shield may be turned upon

its axis when the clamping nuts are loosened, being secured in the position to which it is turned by tightening the clamping nuts.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

The combination with a transparent main wind shield provided with a frame; of a supplemental transparent wind shield provided with a carrier that is coupled with one side of the main wind shield frame; clamps upon said carrier that grip opposite sides of the supplemental shield, each clamp comprising a back portion upon one side of the supplemental shield, ears connected with said back portion and upon the other side of the supplemental shield; a member in hinge connection with said ears, and a screw in threaded connection with the outer portion of said hinged member and, when turned, engaging said back portion to force the inner portion of the hinged member toward the supplemental shield; a threaded stem upon the back portion of each clamp and passing through the carrier for the supplemental shield; and a nut upon each clamp stem, the carrier for the supplemental shield having portions interposed between said nuts and the clamp body portions.

In witness whereof, I hereunto subscribe my name this 25th day of May, A. D. 1921.

ALBERT B. MUELLER.
